(57) **CLAIM**

The ornamental design for a conically shaped filter, as shown and described.

DESCRIPTION

FIG. 1 is a perspective of a conically shaped filter showing our new design;

FIG. 2 is a front elevational view thereof, with the rear elevational view and left and right side elevational views being identical thereto;

FIG. 3 is a top plan view thereof; and,

FIG. 4 is a bottom plan view thereof.
